UNITED STATES PATENT OFFICE.

MELVIN L. STONE, OF LOWELL, MASSACHUSETTS, ASSIGNOR TO DRAPER COMPANY, OF HOPEDALE, MASSACHUSETTS, A CORPORATION OF MAINE.

AUTOMATIC FILLING-REPLENISHING LOOM.

SPECIFICATION forming part of Letters Patent No. 761,724, dated June 7, 1904.

Application filed January 13, 1904. Serial No. 188,831. (No model.)

To all whom it may concern:

Be it known that I, MELVIN L. STONE, a citizen of the United States, and a resident of Lowell, county of Middlesex, State of Massachusetts, have invented an Improvement in Automatic Filling-Replenishing Looms, of which the following description, in connection with the accompanying drawings, is a specification, like characters on the drawings representing like parts.

Looms of the Northrop type equipped with mechanism to automatically effect replenishment of the filling in the running shuttle, as in United States Patent No. 529,940 and others, require more or less attention from the weaver to refill the filling feeder or hopper in which the reserve supply of filling is supported. A large number of these looms are run by one weaver, as they are usually provided with warp stop-motions; but the weaver must spend a good deal of time in examining the various looms under his charge to see that the filling-feeders do not become empty.

My present invention has for its object the production of means to signal automatically to the weaver or other attendant when the filling-feeder is nearly empty, so that he can at once proceed to that particular loom and fill the feeder. The provision of the signal apparatus gives the attendant more time for his other duties, as he knows that without any action on his part the signal will be given whenever the feeder of a loom requires his attention and before it is completely empty.

The various novel features of my invention will be described in the subjoined specification, and particularly pointed out in the following claims.

The drawing represents the right-hand side of a loom equipped with automatic filling-replenishing mechanism, (the filling-feeder being shown in transverse section,) and one embodiment of my invention is applied thereto.

The filling-replenishing mechanism, including the feeder F to contain a series of circularly-arranged filling-carriers or bobbins b, the transerrer f', mounted to rock on the

stud f, the connected dog m¹⁵, moved into position to be engaged by the bunter C² on 50 the lay A³ when filling replenishment is called for, and the controlling rock-shaft d', may be and are all of well-known construction and operate in a manner familiar to those skilled in the art. The leading filling-carrier b¹⁵ of 55 the series is the one next to be transferred, and then the feeder advances to bring the next adjacent filling-carrier into position for transfer. I have provided means to indicate or signal to the attendant when the feeder is 60 nearly empty, so that it can be reloaded or filled up in ample time to prevent any stoppage due to complete removal of its contents. In the present embodiment of my invention I pivot at 2 a lever 1 on any conspicuous part 65 of the loom—as, for instance, the arch A¹⁵—said lever having at one end a target or signal-disk 3 and at its other end a weight 4 heavy enough to swing the signal-disk into signaling position (see dotted lines) at the 70 proper time. Lower down on the arch a bell-crank 5 6 is fulcrumed, the arm 5 being connected by a link 7 with the lever 1 between its fulcrum and the weight, as herein shown. On the rear side of the feeder-stand A⁷, I have 75 pivotally mounted at 8 a depending finger or detent 9, the lower end of which tends to rest against the filling-carriers as they move intermittently toward the transferring-point. Above its fulcrum the detent is provided 80 with an upturned extension 10, which is pivotally connected to one end of a link 11, the other end of said link being jointed to the arm 6 of the bell-crank.

Referring to the drawing, it will be seen 85 that when the parts are in the position shown the weight 4 acts through the intervening connections to press the detent 9 against the filling-carriers on the rear side of the feeder, and at such time the signal-disk 3 is in its 90 non-indicating position. Supposing that the feeder has advanced until the rearmost filling-carrier b¹⁰ of the series moves beyond the detent, it will be manifest that the weight is then free to drop to dotted-line position, as 95 the detent can swing forward in the direction

of arrow 25. The signal-disk is then elevated into signaling or indicating position (shown by dotted lines) in plain sight above the loom-arch, so that the attendant knows the feeder 5 of that loom is nearly empty. It is desirable to paint the disk 3 bright red or some color which will contrast sharply with surrounding objects to make it as distinctive as possible when moved into signaling position. As 10 shown herein, the signal is given when all but six filling-carriers have been transferred from the feeder; but a greater or less number may be chosen without altering the invention. When the attendant notices the signal, he at once 15 fills up the feeder, and in so doing the detent and signal are returned to the positions shown in full lines in the drawing.

Having fully described my invention, what 20 I claim as new, and desire to secure by Letters Patent, is—

1. In a loom, a rotatable feeder to contain a series of filling-carriers, a transerrer to transfer them one by one to the shuttle, an "empty-feeder" signal, and means to cause the latter 25 to move into indicating position when the major portion of the filling-carriers have been removed from the feeder.
2. In a loom, a rotatable feeder to contain a

series of circularly-arranged filling-carriers, means to transfer them one by one to the shuttle, a pivotally-mounted signal-disk, a connected weight to move it into signaling position, a detent adapted to be engaged by the filling-carriers and held in operative position, and a positive connection between the detent 30 and the signal-disk to retain the latter in non-signaling position, release of the detent by the passage beyond it of the rearmost filling-carrier of the series permitting the weight to move the signal-disk into signaling position. 35

3. In a loom, mechanism to automatically replenish the running filling, including a rotatable feeder adapted to contain a circularly-arranged series of filling-carriers, combined with a visual signal, means to retain it in non-indicating position until only a predetermined 40 number of filling-carriers remain in the feeder, and an actuator to thereupon move the signal into indicating position.

In testimony whereof I have signed my name 45 to this specification in the presence of two subscribing witnesses.

MELVIN L. STONE.
